(57) **CLAIM**

The ornamental design for a multi-port type-C docking station, as shown and described.

DESCRIPTION

FIG. 1 is a top view of a multi-port type-C docking station showing my new design;

FIG. 2 is a left side view thereof;

FIG. 3 is a bottom view thereof;

FIG. 4 is a right side view thereof;

FIG. 5 is a front view thereof;

FIG. 6 is a rear view thereof;

FIG. 7 is a top, front, left side perspective view thereof, shown with the cord in an alternate position for use; and,

FIG. 8 is a top, front, right side perspective view thereof. The broken lines in the drawings depict parts of the multi-port type-C docking station that form no part of the claimed design.

1 Claim, 8 Drawing Sheets
